COMBUSTION CHAMBER FOR A COAL STOVE
AND AN AIR SUPPLY THERETOJulian R. Fellows, Urbana, Ill., assignor to The
Board of Trustees of the University of Illinois,
Urbana, Ill.

Application March 21, 1945, Serial No. 583,905

2 Claims. (Cl. 126—73)

1

This invention relates to a coal stove or the like for use in heating residences and other buildings.

All types of bituminous coal contain large amounts of combustible volatile matter which is not burned completely in the ordinary stove or furnace. This not only wastes much of the fuel value of the coal, but also results in a dirty atmosphere. Various methods have been proposed for burning the combustible vapors. None of them are adaptable to simple stoves which could be purchased by families whose incomes are in the lower income brackets.

I have invented a lightweight, inexpensive stove which uses the down-draft principle of burning to consume the smoke. This new coal stove requires a minimum of attention, and is easily regulated so that the usable heat can be controlled. The new stove also provides for a storage space which can be filled with coal and will then require no attention for considerable periods of time.

With the coal stove of this invention it is now possible to heat small homes with an efficient consumption of fuel and at extremely low cost. This results in a substantial saving covering those portions of the year in which heating is required.

The invention will be described as related to a typical embodiment of the same set out in the accompanying drawings. Of the drawings, Fig. 1 is a cross-sectional elevation taken along line 1—1 of Fig. 2, of a coal stove embodying the principles of my invention; Fig. 2 is a plan view of the stove of Fig. 1; Fig. 3 is a section taken along line 3—3 of Fig. 1; Fig. 4 is a section taken along line 4—4 of Fig. 1; Fig. 5 is a section along line 5—5 of Fig. 1; and, Fig. 6 is an elevation, partially broken away, of an alternate embodiment of the invention.

The new coal stove illustrated in Figs. 1—5 of the accompanying drawings comprises an outer shell portion 10 holding a fire box 11 divided into a coking zone 12, a coke-burning zone 13, and a combustion zone 14. At the bottom of the stove, and defining the fire box 11, there is located a grate 15. Beneath this grate is an ash receiving chamber 16 which is made accessible by means of an ash door 17. In the door 17 or at other suitable location, there is located an air inlet opening 18 covered with a suitable draft regulator 19. At the top of the stove there is provided a feed opening 20 that is kept normally closed by a door or lid 21, here illustrated as a plug type. It must fit reasonably tight.

2

Attached to the back of the stove, and in communication with the combustion zone 14, there is located a curved radiator 22. This radiator is designed to be heated by the products of combustion and to convey this heat by radiation and convection to the room in which the stove is located. The bottom 23 of the radiator serves as a trap for fly ash. The fly ash may be removed in any suitable way at the side or rear. 10 As shown, the fly ash may be removed by opening the hinged door 24.

The stove has its combustion zone 14 located between the coke-burning zone 13 and the radiator 22. The inner end of the combustion zone, 15 or that portion within the shell 10, is defined by the scoop 27 of a scoop-shaped refractory element 28 made of ceramic or suitable metal fastened in inverted position to the shell 10 of the stove by means of a U-shaped bolt 29. The 20 opposite end of the combustion chamber extends into the radiator, and this end is defined by an inverted box-like structure 30 opened at the bottom. As can be seen from the above description, the gases from the coke-burning zone 13 pass upwardly into the combustion zone 14 and then pass downwardly into the radiator 22 before reaching the chimney through a smoke pipe 31, while the gases from the coking zone come generally downwardly to join the gases from the coke burning chamber just before they enter the combustion zone. In order to provide a combustion surface in the combustion zone a refractory plate 32 is positioned at the top of the combustion zone. In the operation of the stove this refractory plate quickly becomes very hot and provides an effective ignition surface. This is highly desirable, but not essential to operation of the other features of the invention.

In order to provide adequate supplies of air 40 to the various zones, there are located air supply channels within the stove. At the front of the stove there is positioned a primary air channel 33 extending from the space adjacent the grates 15 to near the top of the fire box 11. This channel has a number of small holes 34 communicating with the fire box. At the rear of the stove and beneath the combustion zone 14 there is located a secondary air channel 35 extending from the region adjacent the grate to the entrance to the combustion zone. These two channels are provided so that there can be an adequate supply of primary coking air, primary coke-burning air, and secondary air to the combustion zone. This air, as well as the air which 50 flows through the grate, all enters through the 55

opening 18. The secondary air channel is divided by longitudinal partitions 36 into three small passageways 37 (Fig. 4). In the center one of these passageways there is located a small hole 38 about $\frac{3}{4}$ " in diameter, opening to the outside of the stove for providing a minimum supply of secondary air even when the draft regulator door 19 is closed. Other means of introducing the secondary air may be substituted.

In the roof of the stove, which should otherwise be air-tight, there is located a restricted opening 39 about $\frac{1}{2}$ " in diameter. This hole is positioned in that portion of the roof directly over the forward edge of the scoop. At the top of the stove there is provided a passageway 40 extending from the top of the fire box 11 to the top of the radiator 22. This passageway is provided with a damper 41 which is normally kept in closed position. This by-pass may be avoided by having a door suitably small.

In the operation of my new stove the fire box 11 may be fired with coal through the feed opening 28. The coal at the top of the fire box in what is referred to as the coking zone, is slowly converted to coke progressively upwards from the coke-burning zone 13. As the coke is burned the ashes may be removed through the grate 15, and the fresh coke forced by its own weight into the coke-burning zone. The primary air channel 33 which extends for the whole depth of the coal supplies air to the coking zone and the coke-burning zone through holes 34 in the channel. The number and size of these holes depends upon the size of the stove, and the heat requirements of the stove. In a typical example, the channel is 6" wide and has three vertical lines of $\frac{1}{16}$ " holes $1\frac{1}{2}$ " apart. This is adequate for a stove with a fire box approximately 19" in diameter and 24" deep. The primary air channel 33 is preferably located at the front of the stove opposite the combustion zone and just above the air inlet opening. Air is supplied to the combustion zone by means of a secondary channel located at the rear of the stove and in communication with the combustion zone. In the structure shown air enters the inlet opening 18 into the region beneath the grates 15. From here a portion of the air flows up through the primary air channel 33 for the full length of the coal, another portion through the secondary channel 35 to the combustion zone and the remainder through the grate 15 to the bottom of the coke-burning zone. Such a construction provides an adequate supply of air for coking the coal, burning the coke, and consuming the gases evolved in these two operations. When the air inlet opening 18 is closed by its door 19 adequate supplies of air are provided to the combustion zone through opening 38 to maintain a smokeless pilot fire.

The restricted opening 39 in the roof of the stove supplies air to the top of the coking zone and prevents the accumulation of that critical amount of gas causing the phenomenon known as "puff back." A "puff back" is caused by certain critical amounts of gas and air that accumulate and then ignite with a slight explosion. Restricted opening 39 may be strategically located in such a way that the air passing through it impinges on the surface of the bed of fresh coal in a small area close to the edge of the scoop 27. This air jet is very helpful in eliminating puff back because it localizes the coking process when the regulator 19 is closed and it also tends to maintain a pilot flame in one spot on top of the coal bed which burns the gases which are re-

leased during a hold fire period. The effectiveness of this jet of air may be increased by extending a tube downwardly from air opening 39 for a distance of approximately 4". The opening has an additional purpose in that it prevents the coal in the coking chamber from arching over. It has been found that in most downdraft magazine stoves when the coal is converted to coke it forms a solid mass extending from wall to wall. Portions at the bottom of the coke chamber will fall into the coke-burning zone, but those at the top sometimes form an arch and remain suspended above the coke-burning zone. This is particularly true at low burning rates. The arching over does not occur in this stove because air entering restricted opening 39 causes the coke near the side of the stove immediately beneath the opening to burn out, thereby breaking the arch. It has been found that when the air supplies have been shut off in the stove, as when it is only desired to maintain fire and not supply appreciable quantities of heat, when the stove is again put into active operation all the coke beneath the opening 39 has been consumed and the rest of the coke feeds by gravity down into the coke-burning zone. The openings 34 from passage 33 have the same effect during normal operation.

The passageway 40 at the top of the stove is provided so that smoke will not escape from the feed opening 28 when the feed door 21 is removed. The operation is as follows: Before the feed door 21 is opened the damper 41 is turned to open position. This permits all the smoke in the top of the fire box to escape out the passageway 40 into the smoke pipe 31.

The combustion of the gases evolved in operation of the stove takes place in the combustion zone 14. These gases leave the coking zone 12 and coke-burning zone 13, pass into the combustion zone, and are then mixed with secondary air and ignited beneath the refractory element 32.

The fire box 11 should be lined with a refractory material 42 such as heat-resisting brick. It could be constructed however from a suitable metal.

An alternate embodiment of this stove is shown in Fig. 6. This embodiment has no radiator, and the combustion zone 14a extends from the top of the coke-burning zone 13a to the top of the fire box. This combustion zone is vertical and is connected directly to smoke pipe 31a. The combustion zone is separated from the rest of the fire box by a vertical refractory element 43. The embodiment of the invention shown in Fig. 6 is provided with a primary air channel 59 similar to the channel 33 (Figs. 1 and 3) and a restricted opening 51 similar to the opening 39 (Fig. 1). This alternate form of stove is still cheaper to construct than the first form, and also provides for the efficient consumption of coal.

Tests made on this new stove show that the coal is burned with very high efficiency. The carbon dioxide in the flue gases has been found to be remarkably high under all conditions.

Having described my invention in considerable detail, it is my intention that the invention be not limited by these details but rather be construed broadly within its spirit and scope as set out in the accompanying claims.

I claim:

1. A coal stove and the like comprising a fire box having therein a coking zone and a coke-burning zone, a combustion chamber in communication with but separate from said zones,

said combustion chamber extending partially inside and partially outside of the fire box, a grate beneath the fire box, a roof above the fire box, a flue communicating with the combustion chamber, means for supplying air to said zones and said combustion chamber, and a scoop-shaped refractory element fastened in inverted position to the inner side of the stove with the scoop portion of said element defining the fire box end of the combustion chamber, said scoop portion having the hollow part thereof toward the center of the combustion chamber.

2. A coal stove or the like comprising a fire box having therein a coking zone and a coke-burning zone, a combustion chamber at one side of the stove communicating with but separate from said two zones, a grate below the fire box, a roof above the fire box with a feed opening therein having a tightly fitting door, a flue communicating with the combustion zone, an air inlet below the grate, a perpendicular channel extending substantially the entire length of the fire box communicating with the air supply and having spaced perforations communicating with the coking and coke-burning zones of the fire box, a second perpendicular channel located adjacent to but separated from the coke-burning zone and extending to the combustion chamber from the bottom of the stove, said second channel communicating with the air supply from
